6 Claims. (Cl. 92—44)

1

Our invention relates to paper machines in which a sheet of paper is initially formed on the surface of a traveling foraminous carrier such as a Fourdrinier wire screen.

The foraminous carrier or screen of such machines forms, as a rule, an endless band which travels from a breast roll to a couch roll, the latter being usually driven from the line shaft of the machine. The wet paper stock is charged onto the screen near the breast roll and is dried while on its way towards the couch roll, in order to attain the required consistency and strength before it leaves the screen at the couch roll prior to passing through the subsequent sections of the machine including, for instance, presses, calenders and driers.

It has been found favorable to provide such paper machines with an auxiliary couch roll between the breast roll and the main couch roll and to place a suction box inside the auxiliary roll to remove water from the paper stock.

Our invention, more specifically, refers to paper machines having an auxiliary couch roll of the just-mentioned type and consists in improvements relating to the drive and control of the auxiliary couch roll relative to the operation of the main couch roll drive.

It is an object of the invention to provide a paper machine in which the drive of the auxiliary couch roll is so controlled as to reduce or prevent the occurrence of slippage between the auxiliary couch roll and the traveling foraminous carrier, thereby eliminating excessive wear of the carrier and contributing to a smooth operation of the Fourdrinier section of the machine.

It is also an object of the invention to provide an auxiliary drive for the Fourdrinier wire which will be so controlled as to not only provide the required driving effort of the auxiliary roll, but also to relieve to an optimum degree the main couch roll drive of driving effort and thus reduce or prevent the occurrence of slippage between the main couch roll and the Fourdrinier wire.

The invention aims also at obtaining a torque control of the auxiliary couch roll drive in such a manner as to limit the power transfer between auxiliary couch roll and Fourdrinier wire screen in dependence upon the degree of vacuum in the suction box of the auxiliary couch roll.

Another object of our invention in conjunction with the foregoing is to provide a separately driven auxiliary couch roll whose speed of rotation is automatically kept within desirable limits in proportion to the speed of the main couch roll drive, and which is controlled to develop a

2

torque within the capacity of the surface portion or arc of contact of the auxiliary couch roll with the foraminous carrier and/or in accordance with the pressure exerted on the auxiliary roll by the charged foraminous carrier.

A still further object, subsidiary to the one last mentioned, is to provide the drive of an auxiliary couch roll with a torque control which operates in dependence upon the degree of pressure of a suction box disposed within the auxiliary roll so that an increase in vacuum and hence an increased pressure of the foraminous carrier against the roll surface is met by an increased torque of the auxiliary couch roll motor thus providing increased capacity for power transmission of the auxiliary roll.

It is also an object of our invention to devise a paper machine drive, as set forth hereinbefore, in such a manner that the desired speed and torque control is effected without the use of contactors and the like circuit interrupting devices in the main control circuit, so as to achieve a continuous and gradual control operation over the entire intended range of control.

Our invention aims also at providing an auxiliary couch roll drive, speed and torque controlled in accordance with the foregoing objects, that is automatically rendered inoperative when the main couch roll drive is disengaged and when the Fourdrinier section has decelerated below a given minimum speed, thereby providing a cut-off effect with a delay corresponding approximately to the deceleration characteristic of the Fourdrinier section in order to prevent overstress on the carrier during stopping periods.

The foregoing objects and the means provided by our invention for achieving the desired results will be understood from the following description of the embodiment exemplified by the drawing in which

Figure 1 represents diagrammatically the web-forming section of a paper machine together with a control system according to the invention,

Fig. 2 is a modified form of part of the system according to Fig. 1, and

Fig. 3 represents diagrammatically another embodiment of a paper machine control designed and operative in accordance with the invention.

In order to facilitate comparing the different embodiments with one another, the last two digits of the reference numerals applied to Figs. 2 and 3 are identical with the respective reference numerals of Fig. 1 wherever similar or similarly functioning elements are designated thereby.

Referring to Fig. 1, the wet section of the illus-

trated machinery comprises a main couch roll MC and a breast roll BC with an auxiliary couch roll AC located between them. An endless foraminous element such as a Fourdrinier wire screen 1 engages the rolls BC, AC, and MC and is guided along its path of motion by one or the several guide rolls such as the one denoted by numeral 2. A number of suction boxes 3 are located adjacent the traveling carrier 1 in order to remove water from the wet paper stock or pulp entrained by the wire screen. Another suction box 4 is located immediately adjacent to the auxiliary couch roll AC and preferably, as shown, in the interior of this roll. The main couch roll may also be provided with a suction box such as the one indicated at 5. The cylindrical walls of the rolls AC and MC are perforated to permit the suction effect to act on the paper stock. The wet pulp is brought onto the traveling wire screen 1 at a location near the breast roll BC and forms a layer 6 which assumes gradually a more solid consistency as it travels along the suction boxes until it reaches the main couch roll MC. At this point, the web leaves the wire screen, passing along guide rolls, such as roll 7, to other sections of the machine, for instance, through the press indicated at 8.

The traveling motion is imparted to the wire screen 1 by a main drive which acts upon the main couch roll MC. To this end, the shaft 10 of roll MC is connected by a bevel gearing 11 with an intermediate shaft 12. A coupling 13 serves to connect this shaft with a cone pulley 14 which is driven by a belt 15 from a cone pulley 16 on the line shaft LS of the machine. The line shaft LS extends along the paper machine and serves also for driving other sections such as roll presses, calenders, and the like devices. A motor LM of adjustable speed, consisting of any available source of motoric power such as a steam engine or other prime mover or an electric motor, serves to drive the line shaft LS. The coupling 13 is provided with a manual control lever 17 associated with an electric contact device 18. The contact at 18 is closed only when the coupling 13 is clutched in and, hence, when the drive of the main couch roll MC in operation.

An auxiliary or helper drive acting on the auxiliary couch roll AC is provided for imparting thereto a positive motion in the direction of travel of the wire screen 1. This helper drive is of the variable voltage type and comprises a direct current motor AM in connection with a main generator MG. A shaft 20 or other suitable mechanical transmission connects the armature 21 of motor AM with the auxiliary couch roll AC. The field winding 22 of motor AM is energized through an adjusting or calibrating rheostat 23 from the mains X and Y of an exciter generator EX which supplies direct current of constant voltage. This exciter forms part of a motor generator set which includes also the above-mentioned main generator MG and has a common shaft 26 driven by a constant speed motor CM. The armature 31 of the exciter EX has its output terminals connected to the above-mentioned mains X and Y. A shunt field winding 27, energized from mains X and Y through an adjusting or calibrating rheostat 28, provides self-excitation. It will be understood that a shunt field winding may be used instead of or in addition to the shunt field winding 27, or that any other suitable source of constant direct current voltage may be employed for energizing the control system.

The armature 41 of the main generator MG is series connected with the armature 21 of motor AM through a resistor 40 which serves as a metering device for a purpose to be described in a later place. The main generator MG has two cumulatively acting field windings 42 and 43. These two field windings are supplied with direct current excitation which is varied in dependence upon the speed of the main couch roll MC and also in dependence upon the torque requirements of the auxiliary couch roll AC as imposed thereon by the wire screen 1 and paper stock under the effect of the suction means. In order to achieve such a combined control and in accordance with the objects of the invention, a combined system of control generators is employed which comprises a regulating generator RG and a pilot exciter PE in conjunction with a bridge type control network BR interconnecting these two generators and providing the field excitation for the main generator MG.

The regulating generator RG has its armature 51 mounted on the shaft 30. A self-excited field winding 52 is series connected with the armature 51 through an adjusting or calibrating rheostat 53 and the diagonal branch A-B of the bridge circuit BR. A second field winding 53 of the regulating generator, hereinafter called the control field winding, is connected across the metering resistor 40 and hence is excited by a voltage which varies in proportion to the current supplied by the main generator MG to the drive motor AM. Another field winding 54 of generator RG, hereinafter called the pattern field winding, is excited from the exciter mains X and Y through a rheostat mechanism PR whose design and operation will be described hereinafter. The control field winding 53 and the pattern field winding 54 act differentially with respect to each other; that is, their resultant field effect on the armature of the regulating generator RG is substantially zero when the current supplied by the main generator MG to the drive motor AM is in accordance with a value of excitation imposed on the pattern field winding 54 by the rheostat mechanism PR.

The self-energizing field winding 52 has the resistance of its circuit adjusted so that the resistance line is approximately coincident with the no load saturation curve. With this adjustment, the self-energizing field will furnish the major portion of the magnetomotive force necessary to maintain the output voltage of the regulating generator so that only a small magnetomotive force is required from either of the other two fields under normal conditions. Since, as mentioned, the control field produced by winding 53 and the pattern field produced by winding 54 are normally balanced when the proper current is flowing in the circuit of the auxiliary couch roll motor, the regulating generator RG has the effect of compensating the voltage of the main generator MG so as to maintain an armature current in the drive motor AM in accordance with the setting of the rheostat mechanism PR.

The pilot exciter PE has its armature 61 driven by the intermediate drive shaft 12. The field winding 62 of generator PE is energized from the exciter mains X and Y through an adjusting rheostat 63. Since this excitation remains constant, the output voltage of generator PE varies in proportion to the speed of the main couch roll MC. This voltage is imposed on the second diagonal branch C-D of the bridge circuit BR. The two field windings 42 and 43 of the main

generator MG are disposed in two opposite legs of the bridge circuit, while the remaining two legs are formed by resistors 85 and 86. These four legs of the bridge circuit are balanced. Consequently, the current from the pilot exciter PE flowing through the bridge causes no voltage drop across the terminals A—B to which the regulating generator RG is connected. Similarly, the current flowing from the regulating generator RG through the bridge causes no voltage drop across the terminals C—D to which the pilot exciter PE is connected.

The potentiometric rheostat mechanism PR is actuated by a diaphragm motor DR. The housing of this motor is connected by a conduit 88 with the suction box 4 of the auxiliary couch roll AC and contains a spring biased diaphragm 81 which is deflected in opposition to the force of its spring in accordance with the magnitude of the vacuum effective in the suction box 4. Diaphragm motors of this type are available in different constructions and are not part of the present invention proper since any suitable pressure responsive actuating device may be used. A movable link 82 is connected with the diaphragm 81 so as to be moved vertically in accordance with a diaphragm deflection. The link 82 cooperates with two sets 83 and 84 of leaf springs which at one extremity are firmly attached to a rigid insulating carrier. While the other end of each leaf spring carries a contact. The leaf springs of both sets 83 and 84 are electrically connected to a corresponding number of steps of two resistors 85 and 86, respectively. When the actuating link 82 is moved upwardly, it will cause the leaf springs of set 83 to contact each other progressively, thereby short-circuiting a progressive number of steps of resistor 85 and reducing the effective total resistance of resistor 85. Similarly, when the actuating link 82 moves downwardly, it will cause the leaf springs of set 84 to short circuit a progressive number of steps of resistors 86.

Rheostat mechanisms of the just mentioned leaf spring type are known and are more fully described in U. S. Patent 2,249,826 to C. R. Hanna. It will be understood, however, that the use of this particular type of potentiometric device is not essential to the present invention and that, if desired, other type devices may be used instead.

The midpoint between resistors 85 and 86 is connected with one terminal of the above-mentioned pattern field winding 54. The remaining terminal of resistor 86 is connected through an adjusting rheostat 87 with exciter main Y and hence with the other terminal of the pattern field winding 54. The remaining terminal of resistor 85 is connected through another adjusting rheostat 88 with exciter main X through the contact 18 of a control relay CR whose relay coil 77 is controlled by the contact 76 of a timing relay TR. The main operating coil of the timing relay is denoted by 73, while numeral 74 represents a neutralizing coil which is separately excited through an adjusting rheostat 75. This rheostat permits selecting, between limits, the timing period of the relay. The control system contains also a voltage relay VR whose coil 71 is connected across the armature 61 of the pilot exciter PE and responds to a given minimum voltage and hence to a corresponding minimum speed of the main couch roll drive. The contact 12 of the voltage relay VR is interconnected with the control relay CR and the coupling contact 18.

The control system is in operative condition after the constant speed motor CM has assumed its normal speed of rotation. When the clutch 13 is engaged by actuating the lever 17, the main couch roll MC and the Fourdrinier section of the machine are driven at a speed determined by that of the line shaft motor LM. The clutch contact 18 closes the circuit of coil 73 of the timing relay TR so that the appertaining contact 76 is closed. This establishes an energizing circuit for coil 77 and hence causes the control relay CR to close its contact 18. As a result, the resistors 85 and 86 of the rheostat mechanism PR are now connected with the exciter mains X and Y for energizing the pattern field winding 54. The pattern field causes the regulating generator RG to supply energization to the generator fields 42 and 43. As a result the motor AM of the auxiliary couch roll AC is energized so as to develop a torque which corresponds to the setting of the vacuum controlled rheostat mechanism. With an increase in vacuum, the actuating member 82 of the diaphragm motor DR will move upwardly, thus reducing the effective total resistance of resistor 85 and increases the effective total resistance of resistor 86. This increases the voltage across the pattern field 54. Consequently, the current supplied by the main generator MG to the drive motor AM is also increased. In this manner, an increased vacuum is accompanied by an increase in torque of motor AM. Similarly, when the vacuum in suction box 4 decreases, the actuating member 82 of the diaphragm motor DR is lowered, thereby reducing the effective total resistance of resistor 86 and increasing the effective total resistance of resistor 85 and decreasing the excitation of winding 54 and hence the current and torque of the drive motor AM. The minimum load obtainable at increasing vacuum is determined by the setting of resistor 87, while similarly the maximum load to be imposed on motor AM at increasing vacuum is determined by the setting of resistor 88.

When during the initial stage of operation the wire screen accelerates or when the speed range of the Fourdrinier section is adjusted over the available operating range, the pilot exciter PE will synchronize the operating speed of the auxiliary drive motor AM with that of the main couch roll MC. At the same time, the regulating generator RG applies the necessary compensation to the field of the power supplying generator MG to hold the driving torque of motor AM at the proper value in accordance with the above described setting and operation of the vacuum controlled regulating means.

When at the end of an operating period the clutch 13 is disengaged, the contact 18 is immediately interrupted while the Fourdrinier section of the machine starts decelerating. It is desirable to maintain the motor AM energized in such a manner that it also continues running at a gradually decreasing speed matching the declining speed of the main couch roll until the Fourdrinier section is substantially at rest. The above mentioned voltage relay VR and the timing relay TR serves to accomplish this result. After the opening of contact 18, the voltage relay VR will at first remain energized because the pilot exciter PE is still running at decelerating speed and hence continues to supply current to the coil 71 of relay VR. However, when the speed of the Fourdrinier section subsides below a predetermined magnitude, for instance 20% of the maximum, the voltage relay VR becomes ineffective

and opens its contact 72. This interrupts the circuit of the main coil 73 of the timing relay TR so that contact 74 of relay TR will be opened. However, this occurs only after the elapse of the timing period adjusted by means of the rheostat 75. The adjustment of this rheostat is so chosen that the time delay is approximately coordinated with the deceleration characteristics of the Four-drinier section.

Due to the above described control of speed and torque of the auxiliary couch roll AC, the slippage of the foraminous carrier relative to the auxiliary couch roll can be reduced or prevented, thereby reducing the wear of the effected machine elements accordingly. This protective function is obtained not only during the normal operating period of the paper machine but also at accelerating and decelerating speeds as well as during speed changes of the main couch roll drive.

Another advantage of a control system according to the invention is the fact that the auxiliary drive motor and the appertaining main generator are permanently connected so that no contactors are required in the main power circuit. The operation of the system is entirely automatic. It will start, stop and change speeds in relative synchronism with the main couch roll without requiring any attention from the attendant. At the same time, the driving effort of the auxiliary couch roll motor is automatically adjusted to provide a torque in correspondence with the vacuum in the suction box and hence with the load and torque requirements of the auxiliary couch roll.

While the above described embodiment of Fig. 1 is especially designed for paper machines in which the main couch roll is driven mechanically from a line shaft, it should be understood that our invention is likewise applicable to other kinds of drives, for instance, to the so-called sectional electric drives in which a separate electric motor is used for operating the different sections of the machine. The individual drive motors are supplied with power from a common main generator and the various sections are started and accelerated by a starting generator. Special control means are provided to transfer from the starting generator to the main or running generator when the operating speed is reached. In this manner, each section is usually started and accelerated independently of the other sections.

The modifications of our invention represented by Figs. 2 and 3 serve to illustrate two different applications of our control system to sectional electric drives of the type just mentioned.

The modification illustrated in Fig. 2 concerns only the portion of the control system associated with the drives of the main couch roll and auxiliary couch roll. Therefore, only this portion of the system is illustrated in Fig. 2, all other elements of the complete system being similar to the corresponding parts as shown in Fig. 1 and described in the foregoing.

According to Fig. 2, the auxiliary couch roll AC whose suction box is connected by a conduit 280 with a diaphragm motor is driven by an auxiliary motor AM whose armature and field winding are denoted by 221 and 222 respectively. The armature 221 is energized by a main generator (not shown in Fig. 2) which corresponds to the generator MG in Fig. 1 and is shafted together with a regulating generator and exciter. The main couch roll MC according to Fig. 2 is driven by an electric motor MM whose shaft drives also the

armature 281 of a pilot exciter PE. The appertaining exciter field winding is denoted by 282. The above-mentioned starting and running generators supply power to a variable voltage bus PB. The main couch motor MM has its armature connected to this bus through the contact 213 of a control switch S. Contact 213 corresponds in functional respect to the coupling 13 shown in Fig. 1 because when the contact is closed the main motor MM is started similar to the switching in of the main drive effected by the closure of coupling 13 in Fig. 1. Switch S according to Fig. 2 is provided with an interlock contact 217, which, as regards its function, corresponds to the switch elements 17 and 18 in the system shown in Fig. 1. The exciter mains X and Y represented in Fig. 2 as well as the voltage relay VR with its coil 271 and contact 272 are similar to the respective elements of Fig. 1 and perform substantially the same function. Assuming the power bus PB in the modification of Fig. 2 to be energized, the closure of switch S causes the motor MM to start operating the main couch roll MC and energized a timing relay (not shown in Fig. 2) which, as in the embodiment of Fig. 1, causes a control relay to place the regulating generator set in operating condition. When the main motor MM reaches sufficient speed, the corresponding increase in output voltage of the pilot exciter PE causes the voltage relay VR to close its contact 272. The further operation of the system is the same as that described previously in conjunction with Fig. 1.

In the embodiment shown in Fig. 3, the Four-drinier wire 301 passes over a main couch roll MC and an auxiliary couch roll AC which contains a suction box 304 connected by a conduit 300 with a diaphragm motor DR for controlling a rheostat device PR substantially in the manner described above in conjunction with Fig. 1. The main couch roll MC is driven by a main motor MM and the auxiliary roll AC is driven by a separate motor AM. Motor AM has two cumulatively acting control fields 322 and 323. The main motor MM receives constant field excitation. Both motors are energized by adjustable voltage from a starting generator SG or a running generator GG depending upon which of the contacts 300 and 301 is closed. While these contacts are schematically illustrated as knife switches, it will be understood that they consist usually of a control device designed to secure the proper sequence of operation. The armature circuits of motors MM and AM extend through a switch 303 which is mechanically coupled with an interlock contact 304 for controlling the operation of a voltage relay VR and a timing relay TR. The coil 371 of relay VR is connected across the armature of motor AM. The contact 372 of relay VR lies in parallel to the interlock contact 304 for controlling the energization of the control coil 373 of a timing relay TR whose contact is denoted by 376. Excitation for coil 373 is supplied by the mains X and Y of an exciter generator EX. A control relay CR has its coil 385 connected between the exciter mains X and Y under control by the relay contact 376 and operates two contacts 386 and 387. The exciter EX has its armature mounted on the shaft of a regulating generator RG which is driven by a constant speed motor CM. The armature 381 of regulating generator RG is acted upon by a self-excited field winding 382, a control field winding 383 and a pattern field winding 384. Windings 383 and 384 operate differentially with respect to each other, and the self-exciting wind-

ing 352 has its circuit so rated that its resistance line is approximately coincident with the no load saturation curve of the generator.

The armature 351 of generator RG is connected across the terminal points A and B of a bridge circuit BR. The two other diagonal points C and D of circuit BR receive constant excitation from the exciter mains X and Y. The four bridge branches are formed by two resistors 360 and 370 and by the above-mentioned field windings 322 and 323 of motor AM. When the operation of the system is started, a contact 393 is closed, thereby also closing the interlock contact 394. Then the contact 391 is closed, thereby energizing both parallel connected motors MM and AM by power supplied by the starting generator SG. At a later time, when the motors have sufficiently accelerated, contact 390 is closed and contact 391 opened so that the further operation is performed under power supplied from generator GG. When contact 393 closes, the interlock contact 394 applies voltage to coil 373 so that the timing relay TR picks up and energizes coil 395 of control relay CR which then closes its contacts 396 and 397, thereby placing the regulating generator set into operative condition. The voltage generated in the armature 351 of generator RG is then controlled in dependence upon the excitation of the pattern field 354 and the oppositely acting excitation of the control field 353. The pattern field excitation depends on the operation of the rheostat device PR, and hence is governed by the degree of vacuum in the suction box 304 while the control field 353 is excited in accordance with the load current in the armature circuit of motor AM measured by a resistor 340. Consequently, the resultant field windings 353 and 354 is substantially zero when the current supplied to the motor AM is in accordance with the excitation imposed on the pattern field winding 354 by the vacuum controlled rheostat mechanism PR. The bridge circuit BR contains the two field windings 322 and 323 of motor AM in opposite bridge branches and operates in a manner similar to the function of the bridge circuit described previously in conjunction with Fig. 1, except that the control effect is not imposed on the field of a generator but acts directly on the field of the drive motor AM. As a result, the driving torque of motor AM is maintained at the proper value in accordance with the vacuum pressure measured by the diaphragm motor DR. When the supply of current to the two motors AM and MM is interrupted in order to stop the machine, the voltage relay VR will not be deenergized until the speed drops to a given low value after which the timing period of relay TR becomes effective before removing the regulating generator RG from the control fields 322 and 323 of the motor AM. In this manner the system automatically takes care of maintaining its control function during decelerating periods in accordance with the inertia characteristics of the machine section.

It will be obvious to those skilled in the art that control systems according to the invention may be modified as to details without departing from the gist and spirit of this disclosure. We, therefore, wish this specification to be understood as illustrative rather than in a limiting sense.

We claim as our invention:

1. In a paper machine, the combination of a paper-forming, travelling foraminous member, a main couch roll engaged by said member, a main drive for driving said main roll, an auxiliary couch roll engaging said member ahead of said

main roll in the direction of travel, suction means disposed adjacent said member and close to said auxiliary roll, a motor in driving connection with said auxiliary roll, a main generator connected with said motor for supplying energization thereto and having field means for varying said energization, a pilot generator mechanically connected with said main drive and electrically connected to said field means so as to excite said main generator for operating said motor at a speed approximately proportional to that of said main drive, and control means also connected to said field means for superimposing on said motor a torque control in accordance with the operation of said suction means, said control means comprising a control generator having an armature circuit connected with said field means and two differential field windings for controlling the voltage of said circuit, one of said windings being connected with said main generator so as to be excited in dependence upon the energization supplied to said motor, a source of controllable voltage connected to said other winding, and a pressure responsive control device disposed between said suction means and said voltage source for controlling the latter in accordance with changes in vacuum of said suction means so as to cause an increase in torque of said motor in dependence upon a decrease in vacuum pressure.

2. In a paper machine, the combination of a paper-forming, travelling foraminous member, a main couch roll engaged by said member, a main drive for driving said main roll, an auxiliary couch roll engaging said member ahead of said main roll in the direction of travel, suction means disposed adjacent said member and close to said auxiliary roll, a motor in driving connection with said auxiliary roll, a main generator connected with said motor for supplying energization thereto and having field means for varying said energization, a bridge-type circuit arrangement having two diagonal branches and including said field means outside of said diagonal branches so as to energize said field means in dependence upon the voltage across said diagonal branches, a pilot generator disposed to be driven in accordance with the speed of said main drive and connected across one of said diagonal branches to impress thereon a voltage proportional to said speed, a control generator having an output circuit connected across said other branch to impress another voltage thereon and having two differential field windings for controlling said other voltage, one of said windings being connected with said main generator so as to be excited in dependence upon the energization supplied to said motor, a source of controllable voltage connected to said other winding, and a pressure responsive control device connected between said suction means and said voltage source for controlling the latter in accordance with changes in vacuum of said suction means so as to cause said motor to increase its torque at decreasing vacuum pressure.

3. In a paper machine, the combination of a paper-forming, travelling foraminous member, a main couch roll and a breast roll engaging said member and being spaced from each other so as to lie substantially at the end and beginning respectively of the paper-forming portion of said member when in operation, a main drive for driving said main roll, an auxiliary couch roll engaging said member between said couch roll and 75 breast roll, a suction box disposed within said

11

auxiliary couch roll and adjacent said member, a motor in driving connection with said auxiliary roll, a main generator connected with said motor for supplying energization thereto and having field means for varying said energization, a bridge type circuit having two diagonal branches and including said field means outside of said diagonal branches so as to energize said field means in dependence upon the voltages across said diagonal branches, a pilot generator operative in accordance with the speed of said main drive and connected across one of said diagonal branches to impress thereon a voltage substantially proportional to said speed, a control generator having an output circuit connected across said other branch to impress another voltage thereon and having two differential field windings for controlling said latter voltage, one of said windings being connected with said main generator so as to be excited in dependence upon the energization supplied to said motor, a source of controllable voltage connected to said other winding, and a manometric control device hydraulically connected to said suction means and electrically connected to said source for controlling the latter in accordance with changes in vacuum of said suction box so as to increase the torque of said motor at decreasing vacuum pressure in said suction box.

4. An electric drive for the suction section of a paper machine, comprising a main roll drive, a direct-current helper drive motor having a separately excited field winding and an armature, a main generator having an armature electrically connected to said motor armature for providing controllable voltage therefor and having separately excited field means for controlling said voltage, a pilot generator having means for connecting it to said main drive and being electrically connected to said field means for causing said voltage to vary in dependence upon the speed of said main drive, a regulating generator having an armature connected to said field means for superimposing a regulating effect on said voltage and having a control field winding for controlling said regulating effect, an auxiliary motor mechanically connected to said armatures of said main generator and said regulating generator for operating them at substantially constant speed, and a control device responsive to suction vacuum and electrically connected to said control field winding so as to cause an increase in torque of said direct-current motor in dependence upon a decrease in vacuum.

5. An electric drive for suction section of a paper machine, comprising a main roll drive, a direct-current helper drive motor, a main generator having an armature series-connected with said helper drive motor and being controlled in dependence upon the speed of said main roll drive to provide for said helper drive motor a voltage variable in dependence upon said speed, said

12

main generator having field means for imposing a regulation on said voltage, a regulating generator having an armature connected to said field means and having two control field windings of differential action relative to each other, one of said control field windings being connected to said main generator and said helper drive motor so as to be excited in accordance with the current flowing from said main generator through said helper drive motor, and suction-responsive control means connected with said other control field winding for exciting it in accordance with variations in suction vacuum so as to cause an increase in torque of said helper drive motor at decreasing vacuum.

6. An electric drive for suction section of a paper machine, comprising a main roll drive, a direct-current helper drive motor, a main generator having an armature series-connected with said helper drive motor and having two cumulative field windings, a bridge circuit having four serially interconnected branches and four terminal points intermediate said branches, said bridge circuit including said two field windings in two opposite ones of said branches, a pilot generator designed to be operated from said main drive and being connected across two opposite ones of said terminal points, a regulating generator having an armature connected across said two other terminal points and having two control field windings of mutually opposing action, one of said control field windings being connected to said main generator and said helper drive motor so as to be excited in accordance with the current flowing from said main generator through said helper drive motor, and suction-responsive control means connected with said other control field winding for exciting it in accordance with variations in suction vacuum, whereby said helper drive motor is controlled to increase its torque at decreasing vacuum.
